UNITED STATES PATENT OFFICE.

CHAUNCEY D. CRANDAL, DECEASED, LATE OF ST. LOUIS, MISSOURI, BY NELLIE A. CRANDAL, ADMINISTRATRIX.

CLAMP.

1,020,129.

Specification of Letters Patent.

Patented Mar. 12, 1912.

Application filed January 24, 1910. Serial No. 539,877.

To all whom it may concern:

Be it known that CHAUNCEY D. CRANDAL, deceased, late a citizen of the United States, and late a resident of St. Louis, Missouri, 5 did invent certain new and useful Improvements in Clamps, of which the following is a specification.

This invention relates to improvements in clamps and has for its object to provide a 10 frame on which is mounted an adjustable cam-operating clamping member for supporting a plurality of strips of material to adhere the same together with glue or the like.

15 In the drawings—Figure 1 is a top plan view of the invention, showing the same in application. Fig. 2 is an enlarged detail top plan view of the adjustable clamp member and the cam-operating means. Fig. 3 is an 20 enlarged detail sectional view of the clamp member and the rigid member, showing the supporting frame broken away.

In the construction of the invention a frame 4 is provided composed of a suitable 25 rod bent to form two parallel members 5. On the free ends of the members 5 is securely bolted a rigid member 6 so arranged as to have its contact surface 7 slightly curved and projecting upwardly a greater 30 distance from the frame and of sufficient size to accommodate the various thicknesses of material to be brought in contact therewith. The said rigid member is suitably held in position by means of the nuts 8 and 35 the locking nuts 9, and in said member is formed an opening 10 which is designed to permit a member to be placed on the upright so that any number of said clamps may be located one above the other. On 40 the frame 4 and slidably mounted upon the members 5 is located the adjustable or sliding member 11. This member consists of the yoke 12, its ends provided with perforated lugs 13 which have bearing upon the 45 parallel members 5, the opposite end 14 of said yoke being likewise provided with perforated lugs 15 which have bearing upon the parallel members 5, and by means of said lugs the yoke is held in position upon the frame and permitted to be adjusted on it at will. In the center portion of the yoke 50 is provided a bore 16 in which is mounted and supported a cam 17, the portion of said cam which is inserted in the bore 16 being of smaller diameter and is held in position

by means of the screw 18 and the plate 19, yet so arranged as to permit said cam to be revolved in the yoke by means of inserting an instrument into the rectangular opening 20 formed in said cam. The upper portion 60 of the cam is arranged to be brought in contact with a contact plate 21. This plate is of suitable rigid material and is provided with openings corresponding with the openings in the lugs 13 and 15 and rests upon the parallel members 5 in advance of the member 14. Said plate is bent rearwardly and its ends bent inwardly to the rear of the member 14 and also provided with openings through which the parallel members 5 65 are passed.

Between the lugs 13 and 15 of the yoke and upon the parallel members 5 are located locking plates 22; each of said plates being provided with openings 23 of a size somewhat larger than the parallel members 5, and the inner ends of said locking plates having recesses 24 so as to permit the upper and lower edge of said plate to slightly project over the upper member of the yoke (see 70 Fig. 2).

Upon the parallel members 5 of the frame and between the lugs 13 and the locking plates are expansive springs 25 which are designed to normally hold the locking plates 85 in an inclined position, as shown in Fig. 2, and while in this position the sliding member is rigidly locked upon the frame. The upper ends 26 of the locking plates project 90 within a short distance of the inner ends of the plate 21 so that by contacting with the plate 21, when the cam 17 is in position as shown by dotted lines in Fig. 2, the plate will contact with the locking plates compressing the springs and causing the locking plates to assume the position as shown by dotted lines in Fig. 2, and when in this position will permit the sliding member to be 95 freely adjusted on the frame.

When placing material between the sliding 100 and rigid members of the clamp, as shown in Fig. 1, and after glue has been placed between the contacting surfaces of the material, the operator then advances the sliding member so that the plate 21 contacts with the material while during this manipulation the contacting surface 27 of the cam is in a position as shown by dotted lines in Fig. 2. The operator then places an instrument or wrench in the opening 20 of the cam 105 110

and by turning the same so that the contacting surface 27 of said cam contacts with the plate 21, the material is forced together. During this operation the two rear inturned 5 ends of the plate are advanced away from the locking plates permitting said locking plates to thoroughly bind and retain the sliding members in rigid position and in this manner the material is thoroughly 10 clamped and the contacting edges brought closely together, the operative position being clearly shown in Fig. 1. When it is desired to remove the material from its clamped position, the instrument or wrench 15 is again inserted in the opening 20 and the clamp released from the plate 21 and placed in a position as shown by dotted lines in Fig. 2, then the plate can be forced rearwardly until its inturned ends contact with 20 the locking plates releasing their frictional contact on the parallel members 5.

Having fully described the invention, what is claimed as new and desired to have secured by the grant of Letters Patent, is:

25 1. A clamp comprising a U-shaped frame formed of a single circular rod, a member rigidly secured to the open end thereof, a sliding member mounted between the side members of the frame and having bearing 30 thereon at its front and rear ends only, a cam mounted on the sliding member, a contact plate slidably mounted in advance of the sliding member, a dog mounted on each side of the sliding member, and having an 35 opening of a slightly greater diameter than the circular rod the edges of said opening adapted to bite the rod and firmly hold the

sliding plate at any point on the frame, the springs for holding the dogs in frictional contact with the frame, and means whereby 40 both dogs may be released simultaneously.

2. A clamp comprising a U-shaped frame formed of a single circular bar, a member rigidly secured at the open end thereof, a sliding member mounted between the parallel members of the frame, having bearing thereon at its front and rear ends, a contact plate slidably mounted in advance of the sliding member and having bearing on the side members of the frame both in front 50 and at the rear of the front bearing of the sliding member, a pair of dogs mounted on the sliding member and having an opening slightly larger than the diameter of the circular bar through which the bar is passed, 55 springs mounted on the bar between the dogs and the rear bearing of the sliding member for holding the dogs in frictional contact with the bar, the edges of the opening adapted to bite on opposite sides of the bar thereby firmly locking the sliding plate 60 at any desired point on the frame and means whereby said dogs may be simultaneously released from contact with the bar, substantially as specified.

In testimony whereof, I have signed my name to this specification, in presence of two subscribing witnesses.

NELLIE A. CRANDAL,
Administratrix of the estate of Chauncey D. Crandal, deceased.
